(57) **CLAIM**

The ornamental design for a LED chip, as shown and described in the drawings.

DESCRIPTION

FIG. 1 is a perspective view of a light emitting diode device showing my new design;

FIG. 2 is a top view thereof;

FIG. 3 is a front view thereof;

FIG. 4 is a back view thereof;

FIG. 5 is a left view thereof;

FIG. 6 is a right view thereof;

FIG. 7 is a cross-sectional view thereof, take along line 7-7 in FIG. 2;

FIG. 8 is a cross-sectional view thereof, take along line 8-8 in FIG. 2;

FIG. 9 is a right side view of thereof; the left side view is a mirror image of the right side view; and,

FIG. 10 is a front view of thereof; the backside view is a mirror image of the front side view.

It will be understood that the dash lines presented in the drawings are for illustration only, and do not form a part of the claimed design.
